UNITED STATES PATENT OFFICE

WILHELM VORWERK, OF BARMEN, GERMANY

HOSE SUPPORTER

Application filed March 19, 1930, Serial No. 437,220, and in Germany February 8, 1929.

My invention relates to hose supporters, more particularly of the type in which a button is connected with a looped part by a strap.

It is an object of my invention to improve 5 a hose supporter of this type, and particularly the connection of the strap with the looped part. To this end I provide a readily detachable connection of the strap and the looped part.

10 In reducing my invention to practice I may provide slots in the looped part for threading the strap through this part, or I may provide a clamp on the looped part which detachably secures the strap to the 15 part.

In a hose supporter according to my invention the strap with the button is readily secured to and removed from the looped part. The hose supporter is simple and can be 20 manufactured at low cost.

In the drawings affixed to this specification and forming part thereof hose supporters embodying my invention are illustrated diagrammatically by way of example.

25 In the drawings:

Figs. 1-3 illustrate a hose supporter in which the strap is threaded through slots in the looped part, and

30 Figs. 4-5 illustrate hose supporters in which the strap is secured to the looped part by a clamp.

Fig. 1 is an elevation of the first-mentioned hose supporter.

Fig. 2 is an end elevation viewed from the 35 left in Fig. 1, and

Fig. 3 is an elevation of the hose supporter with the outer reach of the strap cut away.

Fig. 4 is an elevation of the second-mentioned hose supporter,

40 Fig. 5 is an end elevation, viewed from the left in Fig. 4, and

Fig. 6 is a side elevation showing a hose supporter in which the loop is a separate part.

Referring now to the drawings, *a* is the 45 looped part, *b* is a clasp which is formed by cutting out the looped part, *e* is the strap, and *d* is a button on the strap *e* on which the clasp *b* is placed. The part *a* is secured to the usual pad, not shown, by which it is connected with the leg band.

Referring now to Figs. 1-3, *c*, *c* are two slots near the upper end of the looped part *a* through which the strap *e* is threaded as shown in Fig. 2. The strap is held by friction with its two reaches hanging down at 55 either side of the clasp *b*, concealing the clasp. Serrations may be provided at the edges of the slots for obtaining a better hold of the strap in the slots.

Referring now to Figs. 4 and 5, *f* is a clamp 60 on the looped part *a* for securing the outer reach of the strap *e*.

Referring to Fig. 6, the clamp *f* is provided as described with reference to Figs. 4 and 5, but the looped part is subdivided into a clasp 65 *b'* and a loop *a'*, the loop being inserted in a suitable eye at the upper end of the clasp.

I wish it to be understood that I do not desire to be limited to the exact details of construction shown and described for obvious 70 modifications will occur to a person skilled in the art.

In the claim affixed to this specification no selection of any particular modification of the invention is intended to the exclusion of 75 other modifications thereof and the right to subsequently make claim to any modification not covered by the claim is expressly reserved.

I claim:

80 A hose supporter comprising a looped part, a strap, a button on said strap, adapted to be engaged by said looped part, means for securing said strap to said loop part in a readily detachable manner, and reaches on said strap 85 for concealing said button and said looped part.

85 In testimony whereof I affix my signature.

WILHELM VORWERK.
